BUILDING CONSTRUCTION

Filed Feb. 11, 1924

Patented July 6, 1926.

1,591,443

UNITED STATES PATENT OFFICE.

GEORGE H. SHANK, OF CHICAGO, ILLINOIS.

BUILDING CONSTRUCTION.

Application filed February 11, 1924. Serial No. 692,068.

My invention relates to building construction, and more particularly to building construction of a fireproof nature.

An object of my invention is to make a building construction that can be quickly put up, and is fireproof and sturdy.

Another object of my invention is to construct a building at one-half the cost of building a steel fireproof building.

10 A further object of my invention is to provide a building weighing less than one-half the present weight of a steel fireproof building constructed by the methods now prevailing.

15 Another object of my invention is to eliminate all carpenter form work, carpentry, metal or otherwise.

20 A still further object of my invention is to provide a construction which permits of easy insertion of pipes for plumbing and gas, as well as the running of electrical lines, and in which the pipes are fully protected and may be held firmly in place.

25 Yet another object of my invention is to provide a building construction in which the pipes are insulated by reason of the construction which surrounds them.

With these and other objects in view, which may be incident to my improvements, 30 the invention consists in the parts and combinations to be hereinafter set forth and claimed, with the understanding that the several necessary elements comprising my invention, may be varied in construction, 35 proportions and arrangement, without departing from the spirit and scope of the appended claims.

In order to make my invention more clearly understood, I have shown in the accompanying drawings means for carrying the same into practical effect, without limiting the improvements in their useful applications to the particular constructions which for the purpose of explanation, have been 45 made the subject of illustration.

In the drawing:

Figure 1 is a view in perspective, and partly in section, showing a wall construction and a floor construction embodying my invention.

50 Referring to the drawing, I have illustrated a building construction comprising U-shaped floor beams 1 having upper horizontal flanges 2 and lower horizontal flanges 3. The upper and lower horizontal flanges are connected by webs 4. These floor beams

are suitably fastened to some supporting structure, and pre-cast slabs 5, of some suitable fire-proof composition, are laid in place to rest against the lower flanges 3 of the 60 floor beams. After the pre-cast slabs are put in place, fire-proof composition 6 is poured in place to fill the enclosure made by the floor beams 1 and the pre-cast slabs 5.

Adapted to rest on the top of the upper 65 flanges 2 of the floor beams 1, is a metal lathing construction 7, which may be any one of the usual types. In the present instance I have shown it as of the dove tail type. After the metal lathing 7 is in place, some 70 suitable composition, such as cement 8 of the type used for flooring, is poured in place over the metal laths to form a layer. At stated intervals, wooden cleats 9 are put in place and divide the cement 8 into different 75 sections. The wooden cleats 9 are adapted to support tongue and groove or any other suitable type of flooring 11, which rests on the wooden cleats.

The bottom of the pre-cast slabs 5 and the 80 lower flanges 3 of the floor beams 1 are covered by a layer of plastering or composition 12, such as is usually used for finishing the ceilings of rooms. This layer 12 forms the ceiling of the room below the floor just 85 above described. A construction to provide for a lowered ceiling construction is illustrated at 13 of the drawing. In this type of construction, the floor beams 1 are on a lower level than is the case of the other floor 90 beams referred to. Some suitable composition 14 may be slipped over one of the lower flanges 3 of one of the floor beams. This construction may be pre-cast or cast on the floor beam as desired, and is preferably 95 formed with a shoulder portion 15 which permits the plaster 12 to fit in above the shoulder 15, and tends to key the plaster to the construction.

I have illustrated a wall partition which 100 is formed by means of a U-beam 16 having a broad base and short upstanding sides 17. The U-beam is laid on the upper flanges 2 of the floor beams, and adapted to have their ends rest on the base of the U-beam 16 are 105 wall partition U-beams 18 having flanges 19 projecting at right angles. The U-beams 18 are made of such a size that their ends snugly fit in between the sides 17 of the U-beam 16. Pre-cast slabs 21 are placed inside the flanges 19 of the U-beams 18, and some suitable fire-proof composition 22 is 110

oured into the mould made by the U-beams 18, the U-beam 16 and the pre-cast slabs 21. Plaster, or some suitable wall composition, is placed over the exterior surfaces of the pre-cast slabs 21 and against the flanges 19 of the U-beams 18. The flanges 19 are provided with keys 23 so that the plaster will stick to them.

In the same manner, the lower flanges 3 10 of the floor beams 1 may be provided with keys to hold the plaster or surfacing composition 13.

While I have shown and described the preferred embodiment of my invention, I 15 wish it to be understood that I do not confine myself to the precise details of construction herein set forth, by way of illustration, as it is apparent that many changes and variations may be made therein, by those skilled 20 in the art, without departing from the spirit of the invention, or exceeding the scope of the appended claims.

I claim:—

1. A floor construction comprising a supporting metallic framework, flanges on the lower side of the framework, pre-cast slabs adapted to rest on the inner side of said flanges, hardening material poured on top of the slabs and lying against the slabs and framework, metallic laths resting on the upper side of the supporting metallic framework, a composition layer poured over said laths and covering them, cleats of relatively soft material laid on the composition layer, 35 and a layer of boards supported by the cleats.

2. A floor construction comprising, U-shaped beams, pre-cast slabs bearing against the lower flanges of the U-shaped beam, a hardening material filling the pocket formed by the U-shaped beams and the slab, transverse metallic laths spanning the U-shaped beams, and a composite floor covering and incasing the laths.

3. A floor construction comprising, U-shaped metallic beams, pre-cast slabs bearing against the lower flanges of the U-shaped beams, a hardening material enclosing the spaces between the U-shaped beams and bearing against the pre-cast slabs, metallic laths bearing upon the U-shaped beams and spanning the spaces between the beams, a composite covering over the laths and a wood flooring over the composite covering.

4. A floor construction comprising, U-shaped metallic beams with central flanges, pre-cast slabs adapted to rest upon the central flanges, a hardening material having a bearing upon the pre-cast slabs and filling the spaces between the beam, metallic laths transverse with respect to the beams, a com-

posite cover over the laths, cleats embedded in the composite covering and a wood flooring secured to the cleats.

5. In a floor construction comprising, a series of U-shaped metallic beams, a reinforcing beam comprising a U-shaped beam with a central flange, pre-cast slabs supported by the lower flanges of the U-shaped beams and central flange of the reinforcing beam, a hardening material filling the spaces between the beams and bearing upon the pre-cast slabs, transverse metallic lathing bearing against the beams, equally spaced cleats between the lathing, a composite covering enclosing the spaces between the cleats and interlocking with the lathing and a flooring supported by the cleats.

6. A floor construction comprising, a series of U-shaped metallic beams placed back to back and equally spaced, reinforcing beams comprising a U-shaped beam with central flanges, the central flanges being on a line with the bottom flange of the first mentioned beams, pre-cast slabs bearing upon the central flanges of the reinforcing beam and upon the lower flange of the adjacent beams, a hardening material enclosing the space between the beams and bearing upon the pre-cast slab, transverse metallic lathing bearing upon the beams, cleats supported by the lathing, a composite covering filling the spaces between the cleats and interlocking with the lathing and a floor bearing against the cleats.

7. A floor construction comprising, a plurality of U-shaped beams, a plurality of reinforcing beams comprising U-shaped plates with central flange, pre-cast slabs bearing against the central flange and the lower flanges of the adjacent beams, a hardening material between the beams, a covering for the lower half of the reinforcing beam and a floor supported by the beams and hardening material between the beams.

8. A floor construction comprising, a plurality of U-shaped beams and reinforcing beams, the reinforcing beams having a central flange, pre-cast slabs bearing against the central flange of the reinforcing beams and the lower flange of the adjacent beams, a hardening material enclosing the pockets formed between the beams and pre-cast slabs, metallic lathing laid transverse with respect to the U-shaped beams, a series of parallel cleats embedded between the laths, a composite covering intermediate with the cleats and interlocking with the laths and a flooring laid transverse to and upon the cleats.

In testimony whereof I affix my signature.

GEORGE H. SHANK.
